UNITED STATES PATENT OFFICE.

CHARLES A. GLOVER, OF BELLPORT, NEW YORK.

OIL-SHELL.

No. 841,508.

Specification of Letters Patent.

Patented Jan. 15, 1907.

Application filed October 11, 1906. Serial No. 338,449.

To all whom it may concern:

Be it known that I, CHARLES A. GLOVER, a citizen of the United States, and a resident of Bellport, in the county of Suffolk and State of New York, have invented a new and Improved Oil-Shell, of which the following is a full, clear, and exact description.

The purpose of the invention is to provide a shell adapted to contain oil and to be fired from a cannon or mortar over a body of water to distribute oil thereupon at a point distant from the shore and to so construct the shell that during the major portion of its flight the outlet for the oil will be closed but automatically opened at or about the time the shell strikes the water, thereby permitting the oil to spread upon the rough element and quiet the same.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a longitudinal section through the shell, illustrating its parts in the position they occupy when the shell is not in use. Fig. 2 is a section similar to Fig. 1, illustrating the position the shell assumes in flight and the position of the parts at such time. Fig. 3 is a longitudinal vertical section of the shell, illustrating the position of the parts when the shell has entered the water; and Fig. 4 is a rear end view of the shell with the parts in the position shown in Fig. 3.

A represents a tubular body, which is preferably of consistent diameter throughout, and the outer end of said body is closed by a weighted tip or plug 10, having an internal collar 10^a to fit the bore of a gun, while the opposite or inner end of said body is closed by a slip-cap 11, normally held in place by a bayonet - slot connection 11^a and which is usually provided with a spring 12 upon its inner face adapted to bear against a stopper 13, preferably made of cork, which stopper also tends to close the inner end of the body A and prevents the exit of fluid contained in the body when the cap 11 is removed. The stopper 13, which is a flat disk, is made to fit against a flange 14^a, extending outward from a diaphragm 14, which diaphragm, as

illustrated particularly in Fig. 4, is provided, 55 preferably, with apertures 15. The apertures in the diaphragm 14 are normally closed by means of a valve B, mounted to slide in the body A between its ends. This valve consists of an outer or closing disk 16, 60 an inner perforated disk 16^a, and a connecting-tube 16^b, together with a stem 17, which passes through both disks, being secured to the inner one. The stem 17 also passes through the connecting-tube 16^b and loosely 65 through the diaphragm 14, having a nut 18 at its outer end. The valve-stem 17 is also provided with an annular recess 17^a near its outer end, which is at the opening in the diaphragm 14 when the valve is opened, as 70 shown in Fig. 3, serving to hold the valve in such position while the oil is discharging from the missile.

A ball 19 is located within the body A, being free to travel from the tip or plug 10 to 75 the valve 16, and when said ball 19 engages with the valve 16 it closes said valve.

In the further construction of the body A fins 20 are exteriorly secured thereto at its inner end, as is particularly shown in Fig. 4, 80 and while these fins are shown as four in number they may be more or less as required. The fins 20 at their outer edges are made to taper from their rear ends inward toward the body A; but while such shape of the fins is 85 preferred other forms may be employed.

In operation the shell is filled with oil, as is illustrated in Figs. 1 and 2, and then the outer or weighted end of the shell is introduced into the cannon, the forward ends of 90 the fins bearing against the muzzle. When the cannon is fired, the shell reverses and assumes the position shown in Fig. 2, due somewhat to the fins, which fins tend to guide said shell through the air, steadyng it to some 95 extent and tending to prevent its revolving too rapidly. It may here be stated that when the shell is introduced into the cannon the slip-cap 11 is removed.

As the shell leaves the cannon, assuming 100 the upward inclination shown in Fig. 2, the ball 19 rolls to the inner end of the body A and forces the valve 16 to a seat upon the diaphragm 14, thus causing the stem 17 of the valve to strike the stopper 13 and force it 105 out from the body, as is also shown in Fig. 2. As the shell descends and enters the water the ball rolls again to the tip or outer end of

the body A, as is shown in Fig. 3, and the water will then force the valve 16 inward, uncovering the opening 15 in the diaphragm 14 and permitting the oil in the body A to escape therefrom and flow upon the water.

This shell is exceedingly effective in practice, it is simple and reliable, and is practically automatic in action.

Having thus described my invention, I claim as new and desire to secure by Letters Patent—

1. A shell adapted to contain a liquid and having a weighted outer end, an apertured diaphragm at its inner end, a valve adapted to be seated upon the diaphragm, and an object within the shell for operating said valve.

2. A shell consisting of a tubular body having a weighted outer end, a valve at its inner end adapted to control the outlet of the liquid contained in the body, and a rolling object within the body, adapted to automatically close the said valve in one position of the shell.

3. A shell consisting of a tubular body provided with a weight at its forward end, a removable stopper at its inner end, an apertured diaphragm located opposite the inner face of the stopper, a valve for said diaphragm, the stem of which valve is adapted for engagement with said stopper, and a movable object within the body, adapted to seat the valve and cause its stem to force the stopper out at one position of said shell.

4. A shell consisting of a tubular body provided with a weight at its forward end, a removable stopper at its inner end, an apertured diaphragm located opposite the inner face of the stopper, a valve for said diaphragm, the stem of which valve is adapted for engagement with said stopper, a movable object within the body, adapted to seat the valve and cause its stem to force the stopper out at one position of said shell, and fins ex-

teriorly located at the inner end portion of the body of the shell.

5. A shell consisting of a tubular body, a weight at the outer end of said body, a stopper removably placed within the inner end of the stopper and normally closing said inner end, an apertured diaphragm secured within the body opposite the inner face of said stopper, a valve adapted to close the apertures in the diaphragm, a stem extending from the valve through said diaphragm, adapted when the valve is seated to engage with and dislodge said stopper, a movable weight located within said body, adapted to travel from end to end thereof and when at the inner end of the body to seat said valve, and fins exteriorly located at the inner end portion of the body.

6. A shell consisting of a tubular body, a weight at the outer end of said body, a stopper removably placed within the inner end of the stopper and normally closing said inner end, an apertured diaphragm secured within the body opposite the inner face of said stopper, a valve adapted to close the apertures in the diaphragm, a stem extending from said valve through said diaphragm, adapted when the valve is seated to engage with and dislodge said stopper, a movable weight located within said body, adapted to travel from end to end thereof and when at the inner end of the body to seat said valve, fins exteriorly located at the inner end portion of the body, a slip-cap for the inner end of the body, and a spring-cushion located between said spring-cap and the said stopper.

In testimony whereof I have signed my name to this specification in the presence of two subscribing witnesses.

CHARLES A. GLOVER.
